UNITED STATES PATENT OFFICE.

JOSEPH A. COY, OF LUDLOW, KENTUCKY.

FLASH-LIGHT MACE.

1,206,095.

Specification of Letters Patent. Patented Nov. 28, 1916.

Application filed June 23, 1915. Serial No. 35,787.

To all whom it may concern:

Be it known that I, JOSEPH A. COY, a citizen of the United States, and a resident of Ludlow, in the county of Kenton and State of Kentucky, have invented certain new and useful Improvements in Flash-Light Maces, of which the following is a specification.

My invention relates to devices wherein a lamp is combined with the structure of the device.

The object of my invention is to provide with a lamp a mace or other weapon used by striking therewith, and to insure against damage to or destruction of the lamp incident to the blows of the weapon.

My invention consists in the combination of parts and in the details of construction and arrangement of parts as will herein be more fully described and claimed.

In the drawings: Figure 1 is a side elevation of a mace embodying my invention; Fig. 2 is a partial vertical section on the line $w-w$ of Fig. 1; Fig. 3 is a cross section on the line $y-y$ of Fig. 1; Fig. 4 is a partial side elevation of the tube and its slot; Fig. 5 is a partial side elevation like that shown in Fig. 1, but enlarged to better show the switch construction; Figs. 6, 7, 8 and 9 are partial vertical sections similar to Fig. 2, but showing modifications of the mounting of the lamp with relation to the battery; and Figs. 10 and 11 are partial vertical-sectional elevations showing modifications of the means of attaching the handle mounting to the mace.

My invention, as I prefer to construct it, involves the mounting of an electric battery and a switch for closing circuit through the lamp and battery in the handle of a mace, with the lamp projecting its light from the butt end of the mace.

The mace 1 is of usual construction and formation except that its handle comprises a metal tube 2 which, as shown in Fig. 2, is slipped onto an inner part 3 of the mace 1 up against the bead 4, which is usually provided on a mace, marking the outward termination of the handle part of the mace. This tube 2 may fit the part 3 with a driving fit and held by a screw 3', as shown in Fig. 2, or as shown in Fig. 10, the part 3' and the tube 2' may be threaded to fit each other and thus the tube may be screwed onto the mace 1'. This metal tube 2 may have a covering 5 which is preferably of

leather or may be of any other suitable material to provide a proper surface for a handle. As shown in Figs. 1, 2 and 10, this covering 5 terminates at the bead 4 along with the metal tube 2. As shown in Fig. 11, however, the mace 1' is not provided with any bead, but merely has a shoulder 4' up some distance from where the bead should be, and the metal tube 2' continues up to this shoulder so that the bearing of the tube on the mace is considerably lengthened. The cover 5' extends up to this shoulder 4' along with the tube, and it is this cover 5' that is provided with the bead 5' at the proper location. Immediately inside of the bead 4 or 5', as the case may be, in any of the constructions above described, I prefer to provide a collar 6 which may be of leather, to which is secured, as 75 by sewing, a loop 7 as is usually provided on a mace. This collar 6 is left free to turn on the part of the mace adjacent to the bead, and a stationary collar 8 is fixed around the handle mounting at the other 80 or inner side of the turning collar 6 to hold the collar 6 up close to the bead and support the mace when it is carried by the loop 7. This stationary collar 8 may be corrugated or beaded as shown. The butt 85 end of this tube 2 has a flaring part 9 with a threaded rim 10, and fitted into this flaring part 9 is a reflector 11 with the lamp 12 screwed into its central rear part in an ordinary manner, and with an outwardly 90 extending annular flange 13 fitting against the outer edge of the threaded rim 10. Outside this flange 13 of the reflector 11 the lens 14 has a gasket 15 surrounding its edge and bearing against the flange 13. Over 95 the edge of the lens 14 and its gasket 15 and the flange 13 of the reflector 11, the ring 16 is screwed onto the threaded rim 10 of the flaring part 9 of the tube 2. This ring 16 has, at its outer side, a radially inwardly 100 projected annular flange 17 that projects over the edge of the lens 14 with the outer end of the gasket 15 interposed between it and the lens, so that this ring 16 thus holds the lens and reflector and lamp in position 105 in the butt end of the tube 2. The ring 16 projects past where it is screwed to the rim 10 with an axially extended annular flange 18 which comes tightly over the termination 110 of the covering 5 at this end of the handle to make a tight joint therewith.

By the above means the gasket 15 forms a

5 cushion for the lens 14, preventing chipping of the edge of the lens, and also forms a water-tight joint between the lens and the reflector. The flange 18 making contact with the covering 5 makes a water-tight joint at the other side of the threaded connection of the ring 16 with the tube, while at the same time water is prevented from 10 penetrating between the covering 5 and the tube 2. It will be understood that this covering 5 may be cemented to the tube 2, and it is preferably rather thin, while the tube 2 itself is made as thin as it can be consistent with strength in order to afford a maximum 15 internal diameter without increasing the external diameter of the handle formed by the above described structure.

20 Fitted over the tapering part 9 and the ring 16 at the butt end of the handle is the tapered collar 19 which may be of leather and may be beaded or corrugated as shown. This collar 19 thus forms a finish for the butt end of the handle, making it similar to ordinary mace handles. This collar 19 as 25 well as the collar 8 may be of leather or other similar material like that of which the cover 5 is composed.

25 Constructed as above described, there will be a space left in the interior of the tube 2 from the back end of the lamp 12 up to the inner end of the inner part 3 of the mace. Within this space is mounted the battery 20 of elongated cylindrical formation similar to those obtainable on the market, one end 30 21 of this battery being an exposed electrical conducting surface and forming one pole of the battery, and the other end of the battery having a projection 22 of electrical conducting material which forms the other pole of 40 the battery.

35 The end 21 has, interposed between it and the inner end of the part 3, a spring 23, which is of conical spiral formation with the large end bearing against the end 21 of the battery. Centrally in the inner end of the part 3 is a screw 24 comprising a shank 25 screwed into the wood of the part 3, a head 26 and an intermediate part 27 between the shank and the head which form shoulders 45 adjacent to the shank, while the head 24 forms shoulders adjacent to this intermediate part 27. A switch lever 28 is pivoted on the shank part 25 of the screw and held up against a washer 29 on the inner end of the inner part 3 of the mace by the shoulders formed by the intermediate part 27 of the screw. The small end 50 of the conical spring 23 passes around the intermediate part 27 and is held tightly against the switch lever 28 by the shoulders formed by the head of the screw 24. The switch lever 28 extends out through a slot 29 in the tube 2 adjacent to the inner end 55 of the part 3 of the mace, and on its outer end the switch lever has a knob 30 sur-

rounded by a segment plate 31. The slot 29 is elongated and the switch lever 28 is adapted to swing therein on its pivot formed by the screw 24. The switch lever 28 also extends out through the stationary collar 8 70 which is slotted around the slot 29 of the tube 2, and mounted on the exterior of the collar 8 is a metal guide plate 32 which has a slot 33 through which the lever 28 extends, and which is covered by the segment plate 75 31 at any position of the lever. This slot 33 is substantially straight on both sides and of width only slightly greater than that of the lever 28, but the slot 29 in the tube 2 has a wide part 34 at one end and a narrow part 80 35 at the other end. This wide part 34 is such that the lever 28, as held by the slot 33, cannot make contact with either side or the end of the slot, but the other part 35 is narrow enough that when the lever 28 is 85 swung over into this part it can make contact with the side of the slot 29 next to the inner end of the part 3, being held rigidly against this side of the slot due to its resiliency, and the binding of the lever against 90 the inner end of the part 3 by its pivot screw 24. At the other end of the battery 20 there is a helical spring 36 between the inner or rear side of the reflector 11 and an insulating disk 37, which has, centrally of 95 it, a small helical spring 38 fastened therein and projecting over and making contact with the central terminal part 39 of the lamp 12. This small helical spring 38 projects through the insulating disk 37, and has a contact 40 that lies against the projection 22 of the battery 20, thus supporting the insulating washer 37 against the larger outer spring 36 above alluded to.

100 From the foregoing it will be seen that the battery 20 is held yieldingly between the springs 23 and 36, while, when the switch is closed by swinging the switch lever 28 over to the narrow end part 35 of the slot 29, the circuit is completed from the end 21 of the 110 battery, through the spring 23, lever 28, tube 2, reflector 11, exterior of the lamp 12, through the filament of the lamp, the central terminal 39 of the lamp, and the small helical spring 38, to the other pole of the 115 battery, by means of the contact 40 against the projection 22. Thus the lamp is lighted by pushing over on the lever 28. If the lever 28 is pushed out of the end 35 of the slot 29, the circuit is broken and the lamp 120 extinguished.

120 By mounting the battery 20 with the spring interposed at its ends, the shock, due to the inertia of the battery 20, which is necessarily somewhat heavy, is absorbed by its springs and not transmitted to the lamp 12, which would be injured or destroyed by the impact of the battery upon a blow with the mace were the battery mounted directly against it without any cushioning means. 130

In the modification shown in Fig. 6, the reflector and lens are mounted in the hereinbefore described manner, but the reflector 11', instead of having the lamp 12 screwed into its central rear part, has an opening 41 through which the lamp 12 may extend without contact, and on this reflector 11' are mounted rearwardly extending studs 42, the rear ends of which are fixed in an insulating disk 43 which carries centrally a small helical spring 44 fixed in it and projecting about equally on, both sides. One end of this spring makes electrical contact with the central terminal 39 of the lamp 12 and the other end makes electrical contact with the projection 22 of the battery 20. The lamp 12 is supported laterally by radially extending springs 45 connected to the studs 42 and to a conducting disk 46 fastened around the lamp 12 immediately behind the opening 41 of the reflector, but having a clearance therewith. The front of this conducting disk 46 may be finished like the interior of the reflector to complete the reflection immediately around the lamp 12.

From the foregoing it will be seen that the lamp 12 has a mounting on which it is especially yieldable from impact of the battery 20 which is carried positively against the reflector 11.

In the modification shown in Fig. 7, the arrangement is substantially the same as that of Fig. 2, except that the conducting spring 38 is omitted, and the disk 37 is modified to 35 a washer 37', with a central opening fitting around the projection 22 of the battery 20, allowing the projection 22 to come in contact with the central terminal 39 of the lamp 12.

In the modification shown in Fig. 8, the reflector 47 has its rim threaded to receive the ring 16, holding the lens 14 in position with the gasket 15 interposed. The back 48 of this reflector 47 has the lamp 12 screwed into it in the usual manner, but is prolonged 45 backward and has a closed back 49. The tube 2' has the cap 50 screwed onto it, and a rather stiff helical spring 51 has one end projecting through the cap 50 and rigidly secured thereto as by soldering, and has its 50 other end projecting through the rear end 49 of the reflector and rigidly secured to the reflector in a similar manner. A flexible insulated conductor 52 passes through the back 49 and through the cap 50 with bushings 53 and 54, respectively, around it, and extends 55 through and is fixed in insulating disks 55 and 56 in the reflector and in the tube 2' respectively, having terminals 57 and 58 making electrical contact with the central lamp 60 terminal 39, and with the projection 22 of the battery 20. It will be understood that the tube 2' connects with the other pole of the battery through the switch in the same manner that the tube 2 does in Fig. 2 and as hereinbefore described.

With the above described construction the reflector and lamp are yieldably mounted on the butt end of the mace by means of the helical spring 51, so that any shock on the mace will not be transmitted to the reflector and the lamp contained therein. To reinforce the mounting of the reflector and lamp on the end of the mace I may provide a collar 59 of elastic material, such as rubber, which fits snugly around the rear neck 48 of the reflector and lamp, and also excludes moisture from the butt end of the mace and the rear end of the reflector. The circuit will be from one pole of the battery through the switch and through the tube 2', the heavy spring 51, the reflector 47, the lamp 12, the central terminal 39 of the lamp, the terminal 57, conductor 52, terminal 58 and projection 22 of the battery.

In the modification shown in Fig. 9, the reflector 60 is of cylindrical formation with a flat back 61 which has a central aperture 62, while a disk 63 is placed forwardly of the back 61, and has a neck 64 projecting back through the aperture 62 and fitting snugly around the neck of the lamp 12. The shell 2'', instead of having a flaring part 9 like the shell 2 in Fig. 2, has an enlarged cylindrical part 9'' joining the main part of the shell 2'' through an annular shoulder 65. Back against this shoulder 65 rests the insulating disk 43'', in which is fixed a small helical spring 44'', similar to the spring 44, shown in Fig. 5. This spring bears forwardly against the central terminal 39 of the lamp and rearwardly against the projection 22 of the battery 20. The lamp is yieldably held centrally by radially extending helical springs 66 connected to the outside of the neck 64 of the disk 63 and to backward projections 67 on the reflector 60. Thus the mounting of the lamp is the same as that shown in Fig. 5, except that the disk is placed inside the reflector instead of back of it. Such a construction is more adapted for use where the interior of the reflector is enameled, such cylindrical reflectors being employed because in connection with the enameled material they diffuse the light better than do the parabolic silvered reflectors.

In the construction shown in Fig. 6, it will be seen that the rear of the reflector is open around the lamp, and in Fig. 9 it may be open at intervals, as yieldably mounted. This, I have discovered, eliminates to a considerable extent the darkening effect on the surface of the reflector. Where the rear of the reflector is not open incident to the construction, as in Figs. 2, 7 and 8, I prefer to provide the reflector with small perforations 68 as shown to serve this purpose.

From the foregoing it will be understood that my invention is susceptible to various modifications of its minor details, and therefore I do not wish to be understood as being

limited to the examples specifically shown and described, but

What I claim as new and desire to secure by Letters Patent is:

- 5 1. A mace comprising a solid main part, a hollow handle part, a lamp contained in the butt end of said handle part, a battery contained in said hollow handle part between said lamp and said solid part, an electrical connection between said battery and said lamp, and a switch included in and controlling said connection and comprising a switch lever inside said hollow handle and pivoted on said solid part, said hollow handle part having a transverse slot and said switch lever extending through said slot to be swung transversely therein for operating said switch.
- 10 2. A mace comprising a solid main part and a hollow handle part, a lamp in the butt end of said handle part, a battery contained in said hollow handle part between said lamp and said solid main part, an electrical connection between said battery and said lamp, a radially yieldable mounting for said lamp in said hollow part, and yieldable means between the mounting of said lamp and said battery.
- 15 3. A mace comprising a solid main part and a hollow handle part, a lamp in the butt end of said handle part, a battery contained in said hollow handle part between said lamp and said solid main part, an electrical connection between said battery and said lamp, a radially yieldable mounting for said lamp in said hollow part, yieldable means between the mounting of said lamp and said battery, and yieldable means between said battery and said solid part.
- 20 4. A mace comprising a solid main part and a hollow handle part, a lamp in the butt end of said handle part, a battery contained in said hollow handle part between said lamp and said solid main part, an electrical connection between said battery and said lamp, a radially yieldable mounting for said lamp in said hollow part, yieldable means between the mounting of said lamp and said battery, a switch inside said hollow part on said solid part, controlling said connection, and yieldable means between said battery and said switch.
- 25 5. A mace comprising a solid main part and a hollow handle part, a reflector mounted in the butt end of said handle part, a lamp mounted on said reflector, a battery mounted in said hollow handle part, means yieldably supporting said battery away from said solid part, an electrical connection between said battery and said lamp, and yieldable means between said battery and said reflector whereby the reflector yieldably supports the battery and relieves the lamp of the support of the battery.
- 30 6. A mace comprising a solid main part and a hollow handle part, a reflector mounted in the butt end of said handle part, a lamp mounted in said reflector, a battery mounted in said hollow handle part, an electrical connection between said battery and said lamp, yieldable means between said battery and said reflector, and a laterally yieldable mounting for said lamp in said reflector.
- 35 7. A mace comprising a solid main part, and a hollow handle part of electrically conducting material, a reflector of electrically conducting material held in the butt end of said hollow handle part in electrical connection therewith, a lamp held in said reflector with one terminal electrically connected with said reflector, a battery inclosed in said hollow handle part and insulated therefrom, presenting one of its poles toward said lamp and said reflector, yieldable means between said battery and said reflector, means electrically connecting the other terminal of said lamp with said pole of said battery, and means connecting the other pole of said battery with said hollow handle part.
- 40 8. A mace comprising a solid main part, and a hollow handle part of electrically conducting material, a reflector of electrically conducting material held in the butt end of said hollow handle part in electrical connection therewith, a lamp held in said reflector with one terminal electrically connected with said reflector, a battery inclosed in said hollow handle part and insulated therefrom, presenting one of its poles toward said lamp and said reflector, yieldable means between said battery and said reflector, means electrically connecting the other terminal of said lamp with said pole of said battery, a switch mounted inside said hollow handle part on said solid part and adapted to electrically connect with said hollow handle part, and means electrically connecting this switch with the other pole of said battery.
- 45 9. A mace comprising a solid main part, and a hollow handle part of electrically conducting material, a reflector of electrically conducting material held in the butt end of said hollow handle part in electrical connection therewith, a lamp held in said reflector with one terminal electrically connected with said reflector, a battery inclosed in said hollow handle part and insulated therefrom, presenting one of its poles toward said lamp and said reflector, yieldable means between said battery and said reflector, means electrically connecting the other terminal of said lamp with said pole of said battery, a switch mounted inside said hollow handle part and adapted to electrically connect with said hollow handle part.

part, and an electrically conducting spring interposed between the other pole of said battery and said switch.

10. A mace comprising a solid part and a tubular handle part, a lamp secured in the butt end of said handle part, a battery held in said handle part between said lamp and said solid part, said tubular handle part having a slot through it adjacent to said solid part, which slot is narrower near one end than it is near the other end, a switch lever projecting through said slot into the interior of said handle part adjacent to said solid part, a pivot extending through said switch lever and fixed in said solid part, a spring connected to said pivot and bearing against one pole of said battery, means connecting the other pole of said battery to said lamp, the circuit being completed from said lamp through said tubular handle part, said switch lever and said spring, when said switch lever is brought into the narrower part of said slot and engages with one side of said narrower part.
- 25 11. A mace comprising a solid part and a tubular handle part, a lamp secured in the butt end of said handle part, a battery held in said handle part between said lamp and said solid part, said tubular handle part having a slot through it adjacent to said solid part, which slot is narrower near one end than it is near the other end, a switch lever projecting through said slot into the interior of said handle part adjacent to said solid part, a pivot extending through said switch lever and fixed in said solid part, a spring connected to said pivot and bearing against one pole of said battery, means connecting the other pole of said battery to said lamp, the circuit being completed from said lamp through said tubular handle part, said switch lever and said spring, when said switch lever is brought into the narrower part of said slot and engages with one side of said narrower part.
- 30 12. A mace comprising a solid part and a tubular handle part, a lamp secured in the butt end of said handle part, a battery held in said handle part between said lamp and said solid part, said tubular handle part having a slot through it adjacent to said solid part, which slot is narrower near one end than it is near the other end, a switch lever projecting through said slot into the interior of said handle part adjacent to said solid part, a pivot extending through said switch lever and fixed in said solid part, a spring connected to said pivot and bearing against one pole of said battery, means connecting the other pole of said battery to said lamp, the circuit being completed from said lamp through said tubular handle part, said switch lever and said spring, when said switch lever is brought into the narrower part of said slot and engages with one side of said narrower part.
- 35 13. A mace comprising a solid part and a tubular handle part, a lamp secured in the butt end of said handle part, a battery held in said handle part between said lamp and said solid part, said tubular handle part having a slot through it adjacent to said solid part, which slot is narrower near one end than it is near the other end, a switch lever projecting through said slot into the interior of said handle part adjacent to said solid part, a pivot extending through said switch lever and fixed in said solid part, a spring connected to said pivot and bearing against one pole of said battery, means connecting the other pole of said battery to said lamp, the circuit being completed from said lamp through said tubular handle part, said switch lever and said spring, when said switch lever is brought into the narrower part of said slot and engages with one side of said narrower part.
- 40 14. A mace comprising a hollow handle, a reflector secured in the butt end of said handle, said reflector having a rearward aperture, a lamp inside said reflector and extending loosely through said aperture, a disk fixed on said lamp and covering the aperture around the lamp, a mounting for said lamp on said reflector, and means in said handle for supplying current to said lamp.

JOSEPH A. COY.
